US0D1107661S

(12) **United States Design Patent** (10) **Patent No.:** **US D1,107,661 S**
(45) **Date of Patent:** **** Dec. 30, 2025**

(54) **CABLE CONNECTOR WITH A GROMMET**

(71) Applicant: **IPEX TECHNOLOGIES INC.**,
Oakville (CA)

(72) Inventor: **Tianyuan Yang**, Milton (CA)

(73) Assignee: **IPEX TECHNOLOGIES INC.**,
Mississauga (CA)

(**) Term: **15 Years**

(21) Appl. No.: **29/884,338**

(22) Filed: **Feb. 10, 2023**

(30) **Foreign Application Priority Data**

Dec. 16, 2022 (CA) ..... CA 217904

(51) **LOC (15) Cl.** **09-06**

(52) **U.S. Cl.** **D8/356**
USPC **D8/356**

Assistant Examiner — Denis Houyoux

(57) **CLAIM**

The ornamental design for a cable connector with grommet as shown and described.

DESCRIPTION

FIG. 1 is an exploded top perspective view of a cable connector with a grommet showing the design;

FIG. 2 is an exploded front view of the design shown in FIG. 1, with the rear being identical;

FIG. 3 is an exploded first side view of the design shown in FIG. 1, with the second side view being identical;

FIG. 4 is an exploded top view of the design shown in FIG. 1;

FIG. 5 is an exploded bottom view of the design shown in FIG. 1;

FIG. 6 is another exploded top perspective view of the design shown in FIG. 1; and,

FIG. 7 is a top perspective view of the design shown in FIG. 1.

The broken lines in the figures illustrate portions of the cable connector with grommet that form no part of the claimed design.

1 Claim, 6 Drawing Sheets
